CLAIM

The ornamental design for a can-opening and bag-closing tool, as shown and described.

DESCRIPTION

FIG. 1 is a top front perspective view of a can-opening and bag-closing tool showing our new design;

FIG. 2 is a right side elevational view thereof, viewed from behind FIG. 1.

FIG. 3 is a bottom plan view thereof;

FIG. 4 is a front elevational view thereof;

FIG. 5 is a rear elevational view thereof;

FIG. 6 is a top front perspective view of a second embodiment thereof;

FIG. 7 is a right side elevational view of the second embodiment thereof, viewed from behind FIG. 6;

FIG. 8 is a bottom plan view of the second embodiment thereof;

FIG. 9 is a front elevational view of the second embodiment thereof; and,

FIG. 10 is a rear elevational view of the second embodiment thereof.

Fig. 1.

Fig. 2.

Fig. 4.

Fig. 5.

Fig. 3.

*Fig. 6.**Fig. 7.**Fig. 9.**Fig. 10.**Fig. 8.*
